UNITED STATES PATENT OFFICE.

JOHN COMSTOCK, OF NEW LONDON, CONNECTICUT.

BIT-STOCK OF BRACES.

Specification of Letters Patent No. 10,307, dated December 13, 1853.

To all whom it may concern:

Be it known that I, JOHN COMSTOCK, of the city of New London, in the State of Connecticut, have invented new and useful 5 Improvements in Braces; and I do hereby declare the following to be a full, clear, and exact description, reference being had to the annexed drawings, forming part of this specification, in which like letters in the 10 different figures designate like parts.

The nature of my invention consists in the manner of operating the catch which holds the bit or tool in the brace.

The respective parts not herein otherwise 15 described are made in the usual manner. The respective parts are made of any wood or metal or of wood and metal, as shall be most convenient.

Figure 1 is an elevation of the brace with 20 the bit therein. Fig. 2 is an elevation of the bit. Fig. 3 is a vertical section of the lower end of the brace—the part in which the bit is fastened. Fig. 4 is a transverse section of Fig. 3. Figs. 1 and 2 are half size. 25 Figs. 3 and 4 are full size.

A is a cylindrical ring which fits closely over the lower end of the brace, as shown in Figs. 1, 3, and 4.

b is the catch which slides in a socket in 30 the lower end of the brace, as shown in Fig. 3. The shape of this catch is shown in Fig. 4. This catch slips in the notch of the bit. The cylindrical ring slips around the end

of the brace, being moved by the fingers. Through the ring A is a screw, c, which as 35 the ring is turned, the end of the screw, slides upon the eccentric shaped head of the catch b, pushing it in the notch of the bit, holding it firmly.

d is a helical spring which forces the 40 catch b back after the ring A has been turned back and the screw c has slid off of it.

To use the brace put the bit in the usual socket in the brace with the notch toward 45 the catch b. Then turn the ring A so that the point of the screw c will ride upon the back of catch b. This will force the catch in the notch of the bit, holding it firmly and securely, when it is ready for use. To 50 remove the bit turn the ring back and as soon as the end of the screw is off of the catch the helical spring will push the catch out of the notch.

Having thus fully described my invention 55 what I claim therein as new and desire to secure by Letters Patent is—

The arrangement of the ring, A, with its pin or screw, c, in combination with the eccentric-shaped back catch, b, and the helical spring, d, the whole being combined and arranged substantially as set forth.

JOHN COMSTOCK.
